Fig:2.

INVENTOR.

Joseph H. Pope.

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

NAIL-TRANSFERRING MECHANISM.

Application filed October 2, 1919. Serial No. 327,967.

To all whom it may concern:

Be it known that I, JOSEPH H. POPE, a citizen of the United States, residing at Hamilton, in the county of Essex and State of Massachusetts, have invented certain Improvements in Nail-Transferring Mechanism, of which the following description, in connection with the accompanying drawings, is a specification, like reference characters on the drawings indicating like parts in the several figures.

This invention relates to mechanism for transferring nails, as from the distributing mechanism of a heel-attaching machine to the nail-block from which they are driven.

In my application for Letters Patent filed April 24, 1918, Serial No. 224,428, means is disclosed for locking such transferring or loader mechanism, as it is commonly termed, in its nail-receiving position under the control of the heel and top-lift holder, so that the loader mechanism cannot be operated to deliver a second load of nails to the nail-block until said holder has performed its complete movement, and consequently until the load of nails previously deposited in the nail-block has been disposed of. In some classes of work, however no top-lifts are applied to the heels, and there is no holder movement to effect the control of the loader block.

With such conditions in view, an object of this invention is to furnish novel controlling means for the nail-transferring mechanism. For this purpose, in a machine having controllable actuating mechanism, I control the transfer mechanism with said actuating mechanism. For example, nailing mechanism may be actuated by power mechanism, and in the control of the latter to start or stop the operation of the machine, the action of the loader mechanism may also be determined, it being here shown as latched in its nail-receiving position and released by connection to the controlling means, as the starting lever, only after this has been operated to perform a nailing operation. This insures that the previously delivered load of nails will have been utilized and that the nailing mechanism is ready for the delivery of another load. Upon release, the control of the transferring mechanism may be rendered temporarily ineffective, as by a spring or other means acting to move the transferring mechanism away from the latching

device. As the operator may sometimes desire to move the loader mechanism without starting the machine, independent means, as a plunger operating upon the latch, is also provided for releasing the loader mechanism. 60

In the accompanying drawing illustrating one embodiment of my invention,

Fig. 1 is a front elevation of a heel-attaching machine to which the invention is applied;

Fig. 2 is a detail in side elevation, illustrating a portion of the starting lever and latch connections; and

Fig. 3 is an enlarged detail in vertical section through the latch. 70

For the purposes of this invention, the general construction of the machine is not important. It will be sufficient to say that a frame 10 has fixed upon it a nail-block 12, with the openings of which co-operate reciprocating drivers 14 and to which nails are transferred from a distributing mechanism 16 by a loader mechanism 18. To actuate the drivers and like movable parts of the machine, power is applied under the control 75 of a starting lever 20. This is fulcrumed upon a spindle 22 mounted to turn in the frame and having connections 24 to the usual clutch mechanism (not shown.)

When the loader arm 26 has the openings 85 of its nail-carrying block properly aligned with the delivery tubes 28 of the distributor, it is locked in position by a latch 29 vertically movable in a casing 30 mounted upon the end of a bracket 32 projecting from a portion of the frame. This latch engages an opening 33 in a block 34 adjustably fixed to the upper side of the loader arm by a screw 36 passing through a slot 37. Situated above the latch in the casing and urging it toward the opening 33 is a spring 38. The latch is connected by a wire or other flexible member 40 to the starting lever by means of an arm 42, which is secured to the spindle 22 by a set screw 44. The arm is divided at its outer extremity, and between its portions the wire is clamped by a screw 46 giving a capability for adjustment as to length. The opposite end of the wire is fixed to the center of the upper extremity of the latch 29. Surrounding the wire is a flexible guide tube 48, which adjacent to the arm 42 is clamped by a screw 50 in a divided arm 52 supported upon the spindle 22 and held against rotation therewith by a screw 54 passing through 105 110

a slot in the arm, and being threaded into the frame. The opposite extremity of the guide tube is held in the opening at the top of the casing 30, through which the wire 40 passes, and furnishes an abutment for the spring 38.

Assuming that the loader arm has been swung over the nail-block and has delivered a load of nails thereto, the operator moves it back beneath the distributing mechanism. When this is reached, the opening 33 is beneath the latch 29, which enters it, locking the loader arm against reverse movement. At this time a downward projection 55 from the loader arm presses against a contact member 56 carried in a casing 58 upon a spring-pressed lever 60, the movement of which may be utilized to start the operation of the distributing mechanism 16 to supply a load of nails to the loader block. A shoe being in position for the attachment of its heel, the operator depresses the starting lever 20 to throw in the clutch of the machine and drive the nails contained in the nail-block openings into the heel of the shoe. As the lever is lowered, the arm 42 is turned in an anti-clockwise direction (Fig. 2), applying tension to the wire 40 and raising the latch against its spring 38 from the opening in the loader arm. When the loader arm is thus released, the contact member 56 moves it to carry the opening 33 out of alignment with the latch, so that the arm will not be immediately relocked upon the release of the lever by the operator. The nails in the nail-block have now been disposed of, and the loader arm may be carried over its openings to provide it with a fresh load.

While, ordinarily, the loader arm should not be permitted to be moved from its nail-receiving position while there are nails in the nail-block, certain occasions may arise when its release is desirable under these conditions. For example, the distributing mechanism might fail to fully supply the loader block, in which case the operator would wish to obtain access to it to insert the missing nails by hand. To enable this to be done, manual means is provided for freeing the latch, this being shown as consisting of a plunger 62 mounted to slide in the opening 33 below the latch and retained therein by an enlarged head. This plunger may be raised sufficiently to carry the latch above the block 34, when the member 56 will carry the loader arm out of the latched position, as already described.

Having described my invention, what I claim as new and desire to secure by Letters Patent of the United States is:

1. In a machine of the class described, controllable actuating mechanism for the

machine, nail-receiving means, mechanism for transferring nails to the receiving means, means controlled with the actuating mechanism for controlling the transferring mechanism, and means acting upon said controlling means for independently governing the transferring mechanism. 70

2. In a machine of the class described, nailing mechanism, controllable actuating mechanism for the nailing mechanism, 75 mechanism for transferring nails to the nailing mechanism, and means controlled with the actuating mechanism and including flexible connections for controlling the transferring mechanism.

3. In a machine of the class described, nailing mechanism, controllable actuating mechanism for the nailing mechanism, mechanism for transferring nails to the nailing mechanism, and means controlled 85 with the actuating mechanism for preventing more than one operation of the transferring mechanism for each operation of the nailing mechanism.

4. In a machine of the class described, nailing mechanism, actuating mechanism for the nailing mechanism, controlling means therefor, mechanism for transferring nails to the nailing mechanism, a latch for the transferring mechanism, connections 90 between the latch and controlling means, and means acting to carry the transferring mechanism out of effective co-operation with the latch.

5. In a machine of the class described, 100 nailing mechanism, mechanism for transferring nails to the nailing mechanism, means for locking the transferring mechanism in nail-receiving position, means for releasing the transferring mechanism, and means arranged to move into co-operation with the locking means to independently release the transferring mechanism.

6. In a machine of the class described, nailing mechanism, actuating mechanism 110 for the nailing mechanism, controlling means therefor, mechanism for transferring nails to the nailing mechanism, a latch for the transferring mechanism, connections between the latch and controlling means, 115 and means arranged to manually control the latch.

7. In a machine of the class described, nailing mechanism, actuating mechanism for the nailing mechanism, a member movable by the operator to cause the actuation of the nailing mechanism, mechanism for transferring nails to the nailing mechanism, means connected to said member and controlled thereby for controlling the transferring mechanism, and means acting to render such control of the transferring mechanism ineffective. 120

8. In a machine of the class described, nailing mechanism, actuating mechanism 125

for the nailing mechanism, a member movable by the operator to cause the actuation of the nailing mechanism, mechanism for transferring nails to the nailing mechanism, 5 means for locking the transferring mechanism in nail-receiving position, means controlled by said member for unlocking the transferring mechanism, and independently operable means for unlocking 10 said locking means for the transferring mechanism.

9. In a machine of the class described, nailing mechanism, actuating mechanism for the nailing mechanism, controlling means therefor, mechanism for transferring nails to the nailing mechanism, a latch for the transferring mechanism, connections between the latch and controlling means, and 15 a releasing plunger co-operating with the latch.

10. In a machine of the class described, nailing mechanism, controllable actuating mechanism for the nailing mechanism, a starting lever for the actuating mechanism, 20 mechanism for transferring nails to the nailing mechanism, a latch for the transferring mechanism, and flexible connections including a wire terminating at one extremity in the latch and adjustably secured at 25 the opposite extremity to the starting lever.

11. In a heeling machine, a nail-block, driver mechanism co-operating therewith, power mechanism for the driver mechanism, means for controlling the power 30 mechanism, movable loader mechanism delivering to the nail-block, means for retaining the loader mechanism in nail-receiving position, connections including a 35

wire between the retaining means and controlling means, and a flexible tube surrounding the wire and supported upon the controlling means. 40

12. In a heeling machine, a nail-block, driver mechanism co-operating therewith, power mechanism for the driver mechanism, 45 a starting lever for the power mechanism, movable loader mechanism delivering to the nail-block, a latch for the loader mechanism, a member connecting the latch and starting lever, and a spring effective to move the loader mechanism away from the latch. 50

13. In a heeling machine, a nail-block, driver mechanism co-operating therewith, power mechanism for the driver mechanism, 55 a starting lever for the power mechanism, movable loader mechanism delivering to the nail-block, a latch for the loader mechanism, a member connecting the latch and starting lever, and a releasing member 60 operating directly upon the latch.

14. In a heeling machine, a nail-block, driver mechanism co-operating therewith, power mechanism for the driver mechanism, 65 a starting lever for the power mechanism having an arm movable therewith, movable loader mechanism delivering to the nail-block, a latch for the loader mechanism, a member connecting the latch and starting lever arm, a guide tube surrounding the connecting member, and a holder 70 for the tube supported adjacent to the arm of the starting lever.

In testimony whereof I have signed my name to this specification.

JOSEPH H. POPE.
